UNITED STATES PATENT OFFICE

ISRAEL V. EDGERTON, OF CHICAGO, ILLINOIS, ASSIGNOR TO PALACE POULTRY CAR COMPANY, OF CHICAGO, ILLINOIS, A CORPORATION OF ILLINOIS

POULTRY CAR

Application filed May 19, 1927. Serial No. 192,610.

This invention relates to that class of poultry cars, trucks or the like more especially designed for the transportation of live poultry, an example of this type of poultry car 5 being shown in Letters Patent No. 1,512,215 granted to me October 21, 1924. My present invention is in the nature of an improvement upon a car of this type disclosed in my later Patent, No. 1,699,524, dated January 22, 1929.

10 In poultry cars of the type disclosed in my patents above-identified, the coops for containing the fowls are arranged in superposed tiers on opposite sides of an aisle extending lengthwise of the car, the tiers of coops being 15 arranged at such distances apart as to provide spaces between adjacent tiers to receive troughs from which the fowls may be fed. In my said later patent the feed troughs are supported on the upper edges of spaced vertical plates, each pair of which extends downwardly to the level of the floor of the coop and is provided with horizontal extensions merging with the floors of opposite coops to prevent the fowls from getting beneath the trough 20 supporting plates, as well as to prevent dirt from the floor of each coop spilling over into the underlying troughs. The floor of the car itself provides the floor of the lowermost coop of each series, and where, as heretofore, 25 the supporting plates for the lowermost trough have extended to the floor of the car, this construction has resulted in a narrow channel at the bottom of the narrow trough compartment which rapidly becomes clogged 30 with dirt and waste feed, and is difficult to clean out. The object of my present invention is to provide a construction which will facilitate the cleaning of the floor of the trough chamber.

35 In the drawings—

Fig. 1 is a view in front elevation (looking from the longitudinal aisle outwardly) showing the lower portions of two adjacent tiers of coops and the intermediate trough chamber and troughs;

Fig. 2 is a side elevation of one tier of coops, partly broken out in section, on the line 2—2 of Fig. 1;

40 In the drawings, 10 designates the floor of the car and 11 gratings or screens on one of

the outer side walls thereof. At the inner or aisle ends of the coops are disposed vertical posts 12 that extend from the floor to the roof of the car, these posts preferably being of angle bars. The two posts forming the 55 front corners of a tier of coops are connected together by angle bars 13 that support the floors 14 of all except the lowermost coops, the floors of the latter being constituted by the floor 10 of the car. Similar vertical posts 60 15 are arranged at the outer or rear ends of the coops, these posts likewise extending from the floor to the roof of the car.

The corner posts 12 and 15 of adjacent tiers of coops are separated by a narrow space C 65 which constitutes a trough or feed chamber for the poultry stock, and the aisle ends of the coops are closed by hinged gates D formed with pintles 16 at their lower ends engaged in bearings 17 attached to the posts 12 and 70 15 each having a latch bar 18 that can be lifted to engage at its projecting ends with catches 19 also mounted on the posts 12.

To the inner faces of the posts 12 and 15 are attached brackets 20 and 21 respectively 75 by means of through bolts 22 passed through the parallel limbs of said posts, and to the inner opposed faces of the brackets 20 and 21 are attached a pair of thin flat plates 23 spaced at intervals by inverted U-shaped 80 spacers 24. As shown in Fig. 1, the upper marginal portions of the plates 23 are flared outwardly and their edges curled, as shown at 23' to form supports on which the feed troughs 25 are slidably mounted so as to be 85 withdrawable endwise from the trough chamber C. It will be observed that the plates 23, in the case of all except the lowermost pair of plates, have at their lower ends outwardly extending horizontal flanges 23^a that 90 register with the coop floors 14 so as to prevent dirt on the latter, as well as small chickens, from getting into the trough compartment C.

Describing the side walls of the coops, in 95 the trough compartment C and extending from end to end thereof are arranged upper and lower longitudinal bars or rods 26 and 27. The upper rods 26 are supported at their ends by the lower downwardly offset end 199

portions of the brackets 20, as clearly shown in Fig. 1. Encircling the upper rod 26 is a metal sleeve 28, into apertures in the lower side of which are entered the upper hooked 5 ends of spaced vertical rods 29. The lower hooked ends of said rods are similarly entered through holes in the upper edge of a folded metal strip 30, the lower edge of which latter is formed with a hollow bead 31, in which lies the lower rod 27. The ends of the rod 10 27, as shown in Fig. 1, underlie the upper vertically offset ends of the brackets 20. The folded metal strip 30 is of a height approximately equal to the height of the trough 25 and lies opposite the side of the latter, while the spaced rods or wires 29 thereabove afford ample openings through which the poultry 15 can feed from the trough.

Since the floors 14 of all the coops above 20 the lowermost coop do not extend across the trough chamber C, all waste feed and dirt consequent upon dumping the troughs in the trough compartment drops onto the portion of the car floor 10 that forms the bottom of 25 the trough compartment. Heretofore the trough supporting plates 23 pertaining to the lowermost or bottom coops have extended to the floor of the car, thus forming a narrow longitudinal channel or pit with closed sides 30 for the accumulation of dirt and waste feed, which has proved difficult to clean out and thus unsanitary.

By reference to Fig. 1 it will be seen that in the present construction, the lowermost 35 brackets 20', and trough supporting plates 28^b mounted thereon terminate at a distance above the floor 10 of the car, thereby leaving longitudinal spaces or openings 32 between the lower edges of the plates 28^b and 40 the floor of the car, through which spaces access can readily be had by a suitable scraper or other tool to readily clean out the bottom of the trough compartment, or to flush the same with a hose so as to scour the entire 45 floor of the car. This improved structural feature constitutes a substantial improvement, from a sanitary viewpoint, making it possible to thoroughly clean the floor of the car in an expeditious manner, whereas heretofore it has proved a matter of much difficulty to clean the bottom of the trough compartment.

I have also herein shown another feature of improvement, which consists in a readily 55 detachable means for restricting the feeding space of the coop partition or wall represented by the rods 29, attached to and extending downwardly from the brackets 20 and 21 are metal strips 33 and 34 that terminate in oppositely facing inwardly extending hooks or 60 sockets 35 and 36 respectively. In each pair of sockets 35, 36 is adapted to be supported a thin wooden slat 37, this latter lying crosswise of the rods 29 and being held snugly 65 against the latter by its inherent elasticity or

spring, due to the fact that the hooks or seats 35 and 36 for the ends of the slat are outwardly offset slightly relatively to the vertical planes of the rods 29. Where a poultry shipment comprises only full-sized fowls, the 70 guards 37 are unnecessary and can readily be removed and stored in any convenient place in the car. When the poultry shipment comprises small fowls or large and small fowls mixed, by inserting the slat guards 37 as 75 shown, all danger of the small fowls forcing themselves through the feed slots into the feed troughs is prevented. This improvement thus adapts the described coop structure to serve equally well for the shipment of both 80 large and small sized poultry.

I claim—

In a poultry car, the combination with adjacent vertical tiers of coops, and a relatively narrow trough compartment between said tiers, of trough supports between opposed coops respectively, each comprising a pair of spaced vertical plates adapted to support a trough on their upper edges, the plates of the trough supports pertaining to all except the lowermost coops being formed with lateral extensions meeting the floors of said coops, and the plates forming the trough support of the lowermost or floor coops terminating above the floor of the car, thereby providing 95 lateral openings at the bottom of the trough compartment to afford access for cleaning out the latter.

ISRAEL V. EDGERTON.
